(57) **CLAIM**

The ornamental design for an electronic cigarette, as shown and described.

DESCRIPTION

FIG. 1 is a front elevational view of the first component removed from the a electronic cigarette shown in FIG. 17, for clarity of disclosure;

FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front, right, and top perspective view thereof; and,
FIG. 8 is a rear, left, and bottom perspective view thereof.
FIG. 9 is a front elevational view of the second component removed from the electronic cigarette shown in FIG. 17, for clarity of disclosure;
FIG. 10 is a rear elevational view thereof;
FIG. 11 is a left side elevational view thereof;
FIG. 12 is a right side elevational view thereof;
FIG. 13 is a top plan view thereof;
FIG. 14 is a bottom plan view thereof;
FIG. 15 is a front, right, and top perspective view thereof; and
FIG. 16 is a rear, left, and bottom perspective view thereof.
FIG. 17 is a front elevational view of the first embodiment of an electronic cigarette shown in an assembled configuration of use where the two components shown in FIGS. 1 & 9 are combined;
FIG. 18 is a rear elevational view thereof;
FIG. 19 is a left side elevational view thereof;
FIG. 20 is a right side elevational view thereof;
FIG. 21 is a top plan view thereof;
FIG. 22 is a bottom plan view thereof;
FIG. 23 is a front, right, and top perspective view thereof; and
FIG. 24 is a rear, left, and bottom perspective view thereof.
FIG. 25 is a front elevational view of the first component removed from the electronic cigarette shown in FIG. 41, for clarity of disclosure;
FIG. 26 is a rear elevational view thereof;
FIG. 27 is a left side elevational view thereof;
FIG. 28 is a right side elevational view thereof;
FIG. 29 is a top plan view thereof;
FIG. 30 is a bottom plan view thereof;
FIG. 31 is a front, right, and top perspective view thereof; and
FIG. 32 is a rear, left, and bottom perspective view thereof.

(Continued)

FIG. 33 is a front elevational view of the second component removed from the electronic cigarette shown in FIG. 41, for clarity of disclosure;
 FIG. 34 is a rear elevational view thereof;
 FIG. 35 is a left side elevational view thereof;
 FIG. 36 is a right side elevational view thereof;
 FIG. 37 is a top plan view thereof;
 FIG. 38 is a bottom plan view thereof;
 FIG. 39 is a front, right, and top perspective view thereof; and
 FIG. 40 is a rear, left, and bottom perspective view thereof.
 FIG. 41 is a front elevational view of the second embodiment of an electronic cigarette shown in an assembled configuration of use where the two components shown in FIGS. 25 and 33 are combined;
 FIG. 42 is a rear elevational view thereof;
 FIG. 43 is a left side elevational view thereof;
 FIG. 44 is a right side elevational view thereof;
 FIG. 45 is a top plan view thereof;
 FIG. 46 is a bottom plan view thereof;
 FIG. 47 is a rear, left, and bottom perspective view thereof; and,
 FIG. 48 is a front, right, and top perspective view thereof. The broken lines in the figures are included for the purpose of illustrating portions of the article which form no part of the claimed design.
